(74) Attorney, Agent, or Firm — Carol N. Green Kaul, Esq.

CLAIM

The ornamental design for a cover for electronic communications device, as shown and described.

DESCRIPTION

FIG. 1 is a front perspective view of a cover for electronic communications device showing our new design.

FIG. 2 is a rear perspective view thereof.

FIG. 3 is a front elevation view thereof.

FIG. 4 is a rear elevation view thereof.

FIG. 5 is a left-side view thereof.

FIG. 6 is a right-side view thereof.

FIG. 7 is a top view thereof.

FIG. 8 is a bottom view thereof.

FIG. 9 is a perspective view thereof in an open position; and,

FIG. 10 is a perspective view thereof in an open position.

1 Claim, 8 Drawing Sheets
